UNITED STATES PATENT OFFICE.

GEORGE W. JACKSON, OF CHICAGO, ILLINOIS.

SCOW FOR TRANSPORTING GRAVEL.

1,047,233.

Specification of Letters Patent. Patented Dec. 17, 1912.

Application filed October 24, 1911. Serial No. 656,499.

To all whom it may concern:

Be it known that I, GEORGE W. JACKSON, a citizen of the United States, and a resident of Chicago, in the county of Cook and State of Illinois, have invented certain new and useful Improvements in Scows for Transporting Gravel; and I do hereby declare that the following is a full, clear, and exact description thereof, reference being had to the accompanying drawings, and to the characters of reference marked thereon, which form a part of this specification.

This invention relates to improvements in gravel scows or boats for transporting gravel, or gravel and sand, loaded thereon from the bottom of a lake or other body of water, and the invention consists in the matters hereinafter set forth and more particularly pointed out in the appended claims.

Among the objects of the invention is to provide, in a scow for this purpose, means for loading the gravel on the scow from relatively deep deposits under the water, so arranged as to enable the boat to be uniformly loaded from end to end with an exceedingly simple loading apparatus.

A further object of the invention is to provide improvements in such scow constructions as to facilitate the draining of the water and escape of the finer sand that is discharged into the compartment of the scow, so as to facilitate the handling and loading of the gravel in the scow compartment.

In the drawings;—Figure 1 is a plan view of a gravel scow embodying my invention, with a portion of the loading apparatus omitted. Fig. 2 is a side elevation thereof. Fig. 3 is a transverse section thereof with the loading apparatus omitted. Fig. 4 is a fragmentary plan view, showing the arrangement of the screens and their supports. Fig. 5 is a partial vertical section on the line 5—5 of Fig. 3. Fig. 6 is a perspective view of a clam-shell bucket constituting part of the loading apparatus shown in Fig. 1. Fig. 7 is a side elevation of the scow provided with another form of loading apparatus. Fig. 8 is a partial plan view thereof.

The scow may be of any suitable or preferred design or construction, and is herein shown as a self-propelled scow, with its

propelling power plant, indicated as a whole by 11, located at the stern of the boat.

Disposed along the longitudinal center of the scow is a single, elongated compartment 55 15, which extends from the bottom to the top of the scow, and is open at its top to receive the gravel or other granular material. Said compartment is provided with one or more screens which extend entirely 60 across the horizontal dimensions of the compartment, said screens constituting grading and supporting means for the sand and gravel which is discharged into said compartment, arranged to retain the material 65 of a desired mesh and to permit the material of a finer mesh to drop therethrough.

As herein shown, three superposed screens 16, 17 and 18 are employed, located at suitable vertical distances apart. The upper 70 screen 18 is formed with the largest mesh, the lower screen 16 with the smallest mesh and the middle screen 17 with a mesh intermediate that of the top and bottom screens.

The scow herein shown is designed for 75 transporting gravel only, and the lower screen 16 is located and supported near the bottom of the compartment. If the screens be embodied in a scow having dumping doors, the bottom screen will be located 80 closely adjacent to the door level. The said screens may be supported in any suitable manner on the side and end walls of the compartment. As herein shown the side and end walls are provided with horizontal 85 brackets 19, 19 extending inwardly therefrom and attached to said walls in any suitable manner. Said brackets are shown as made of L shape in cross section. In addition to said brackets I may provide a suitable number of transverse beams 20 which extend between and are attached at their ends to the side brackets 19, as shown in Figs. 4 and 5.

The screens are preferably made of heavy 95 sheet metal plates which are punched to produce the required mesh, and are of sufficient thickness to support the loads of gravel to be carried thereon. Each screen is preferably made of a plurality of sections, especially in the larger size scows, in order to enable the same to be readily handled when

- installing them or replacing them. If desired, when a plurality of screens are employed, the lowermost screen may be substituted by a solid plate or plates in order 5 to retain the sand loaded into the compartment in the lowermost section thereof along with the gravel and other coarser material in the section or sections above the lowermost sections.
- 10 The loading apparatus shown in Fig. 2 embraces a vertically swinging boom 21 that is pivoted at its inner end to the swinging or rotating platform 22 which is supported on a truck 23, that spans the compartment 15. The wheels 24 of said truck travel on parallel rails 25, 25 that are supported on the deck of the scow laterally at the sides of the compartment. Said boom 21 carries at its outer end a clam-shell bucket 26 or like 20 device that is suspended from the outer end of the boom on suitable cables trained over guide sheaves on the boom and back to the controlling drums (not shown) on the platform 22. The said boom is likewise 25 controlled in the rising and falling movements by cables trained over other controlling drums (not shown) on the platform 22. The said platform may carry any suitable form of motor for operating the controlling 30 drums of the boom and bucket, as well as controlling the movement of the truck 23 and platform 22. As herein shown, the operating motor comprises an electric motor 29 which is geared to the controlling drums, 35 platform and truck mechanisms. The shafts of the truck supporting wheels 24 are geared to a driving shaft 30 in any suitable manner, which latter shaft is provided with a gear wheel 31 that meshes with the gear 40 pinion 32 that is mounted on a shaft that is operatively connected to the motor shaft in any suitable manner, whereby the boom carrying truck may be caused to travel from one end to the other of its supporting track 45 rails on the scow. The said truck is also provided with the usual circular rack 33 that meshes with a pinion 34 which is carried by a vertical shaft which is operatively connected with the motor, whereby the platform 50 and the boom carried thereby may be swung or rotated about the pivotal axis of the platform, so that the outer end of the boom and the bucket carried thereby may be swung outwardly over the end of the scow, 55 or over either side thereof to reach the gravel deposits at the end or sides of the scow. The particular construction of the mechanism for controlling the boom and bucket, as well as for controlling the movement of the truck and the boom supporting platform, constitute, in themselves, no part of the present invention, and may be made of any suitable or preferred construction.
- 60 The clam-shell bucket may be lowered at 65 any suitable point at the end or sides of the

scow within reach of the boom, and is operated by the motor driven truck and motor operated platform to discharge the contents of the bucket into any part of the compartment 15. Likewise the boom and its clam-shell or grab bucket may be employed to take up the gravel from the compartment 15 of the scow and carry it to a suitable point for the disposal thereof. When unloading a scow having a plurality of superposed screens, the contents of the upper section of the compartment is first unloaded and the upper screens 18 are then removed. Thereafter the contents of the next lower section of the compartment are unloaded and the next lower screens 17 are removed. Finally the contents of the lowermost section of the compartment is removed, but, ordinarily it is not necessary to remove the lowermost screens, which may be permanently fixed in place.

In order to facilitate the placing of the granular material in the compartment and to carry away the finer sand or material not to be retained, the scow is provided with a 90 water pumping equipment, comprising, as herein shown, a centrifugal pump 36, the intake pipe 37 of which extends through the side of the boat and downwardly a short distance into the water. The outlet side of 95 the pump is connected to a flexible hose 38 which is made of such length as to conveniently serve all parts of the compartment as the material is deposited thereinto. The water is discharged into the compartment, 100 together with the granular material, in such volume that when mixed with the granular material, the mixture constitutes a readily flowable mixture which, by reason of its semi-fluidity, readily spreads throughout the 105 compartment, the water washing or carrying the finer material through the screens and grading the material and depositing each grade of material on its proper screen support.

As a further and separate improvement the side and end walls of the compartment 15 may be made hollow, each wall comprising an inner perforated plate 40 and an outer imperforate or solid plate 41. Said 115 perforated and imperforate plates are spaced apart a distance to provide around the compartment vertical passages 42 which are open at the lower side thereof. The provision of the hollow walls, with the inner 120 members thereof perforated as shown, permits the finer sand and the water to readily escape from the compartment and back into the bottom of the lake or other body of water, so that thereby the loading of the 125 compartment may be hastened, inasmuch as all the water and sand is not required to escape through the bottom screen. The said perforated and imperforate plates of the hollow walls may be spaced from each other 130

by the spacing members 43, which may consist of vertically arranged I-beams, fastened in any suitable manner to the inner and outer plates of the hollow walls.

5 In order to avoid depositing an undue amount of water and sand into the compartment 15 of the scow the walls of the clam-shell bucket may also be perforated, as indicated in Fig. 6.

10 In Figs. 7 and 8 I have shown another form of loading apparatus for raising the gravel and sand from the bottom of a body of water and depositing it into the compartment 15. The apparatus shown in said fig-

15 ures comprises a series of buckets 45, 45, connected in any suitable manner to an endless belt or chain 46, that is trained about suitable pulleys (not shown) carried at the ends of a boom 47 which is pivotally supported at the rear end of the scow and trails rearwardly and downwardly therefrom. Said boom 47 may be supported at the stern of the scow in any suitable manner to permit it to be swung vertically and through a limited range from side to side. As herein shown, the rear end of the boom is provided with a rigid downwardly extending leg 48 which is pivoted at its lower end at 49 to a turn table 50, which latter is rotatively sup-

20 ported on a suitable frame 51 mounted on the deck of the scow. The said turn table may be actuated to turn the same about its pivot 52 by means of a rotative pinion 53 carried by the table and meshing with a circular rack 54 carried by the support 51. Rollers 56 carried by the turn table travel on the support 50 to stably support the table. The said boom 47 may be raised and lowered by any suitable method, as, for instance, the 25 raising and lowering screws 58 suitably supported on the turn table and engaging screw-threaded nuts pivotally carried by the boom. The pinion 53 and the boom raising and lowering screws 58 as well as the bucket chains 30 may be operated from any suitable motor.

The contents of the buckets 45 are discharged into a hopper 60 which in turn discharges the material through the chute 61 onto an endless belt 62 arranged longitudinally over the compartment and trained about suitable rollers 64 located over the scow compartment at the ends thereof. The material may be scraped from said belt or conveyer into the compartment below by 35 means of a scraper device 66 located above the belt, and supported at its ends by standards 67, which are adapted to be supported on the deck of the scow in any suitable manner at the sides of the compartment 15. Said 40 scraper is adapted to be adjusted longitudinally of the belt, and such adjustment may be effected by providing longitudinally spaced sockets along the deck to receive the standards 67. When the belt is located centrally of the compartment the scraper may

be made V-shape, as shown in Fig. 8, so as to deposit the material scraped from the belt on both sides of the compartment. If the belt is located at one side of the compartment a transversely oblique scraper may be 70 employed to scrape the material therefrom into the compartment below.

So far as is concerned the hollow walls of the compartment such walls may be employed in gravel scows of other design. 75 Likewise the structural details of the scow shown may be somewhat varied within the scope of my invention.

I claim as my invention:—

1. A scow for transporting gravel discharged thereinto from a body of sand and gravel beneath a body of water, provided with a compartment which is open at its top and at its bottom, a screen extending across said compartment between its top and its bottom, a boom controlled and supported bucket for raising sand and gravel and depositing it on said screen, whereby the sand is separated from the gravel and falls back to the natural deposit beneath the body of 90 water, and other means for discharging water from said body of water into said compartment together with said sand and gravel.

2. A scow for transporting gravel deposited thereinto from a natural body of sand and gravel beneath a body of water provided with a longitudinally arranged compartment which is open at its top and at its bottom, a screen extending across said compartment, a loading apparatus supported on the scow for carrying the gravel and sand to and depositing the same in said compartment, and constructed and arranged to transfer the contents of the scow from said compartment to a point of disposal exterior thereto, and a water pumping apparatus for pumping the water from said body of water into said compartment.

3. A scow provided with a longitudinally arranged compartment which is open at its top and at its bottom, a screen extending across the compartment and supported on the walls thereof, a loading apparatus comprising a truck arranged over the compartment and provided with wheels that travel on track rails at the sides of the compartment, a boom pivotally supported on the truck, a bucket carried by the outer end of the boom, with means for lowering the same into the gravel deposit beneath the scow and for carrying the bucket above the compartment to dump its contents thereinto, and a water pumping apparatus for pumping water into the compartment.

4. A scow provided with a longitudinally arranged compartment which is open at its top and at its bottom, a screen extending across the compartment and supported on the walls thereof, each of the side and end

walls comprising an inner perforated plate and an outer imperforate plate which are spaced to provide a water escape passage which surrounds said compartment, and
5 means for depositing sand, gravel and water into said compartment.

In testimony that I claim the foregoing as

my invention I affix my signature in the presence of two witnesses, this 19th day of October, A. D. 1911.

GEORGE W. JACKSON.
